CLAIM

The ornamental design for a snow racer carrier, as shown and described.

DESCRIPTION

FIG. 1 is a top plan view of the snow racer carrier showing my new design;

FIG. 2 is a bottom plan view thereof;

FIG. 3 is a front elevational view thereof;

FIG. 4 is a rear elevational view thereof;

FIG. 5 is a left side elevational view thereof;

FIG. 6 is a right side elevational view thereof; and,

FIG. 7 is a complete bottom plan view thereof.

The broken away portions as shown in FIG. 1 through 6 are to display indeterminate length.
